Primary Examiner — Marianne Pandozzi*Assistant Examiner* — Jae Liang(74) Attorney, Agent, or Firm — Thompson Coburn LLP(57) CLAIM

The ornamental design for a bottle with decorative belt, as shown and described.

DESCRIPTION

FIG. 1 is a top perspective view of a bottle with decorative belt showing our new design;

FIG. 2 is a bottom perspective view thereof;

FIG. 3 is a rear view thereof;

FIG. 4 is a front view thereof;

FIG. 5 is a right side view thereof;

FIG. 6 is a left side view thereof;

FIG. 7 is a top plan view thereof; and,

FIG. 8 is a bottom view thereof.

The broken lines shown in the drawings are directed to environment and are for illustrate purposes only; the broken lines form no part of the claimed design.
